8c Inventor,

Thomas W. Allen,

by his Attorneys

Jesson & Jesson

UNITED STATES PATENT OFFICE.

THOMAS W. ALLEN, OF PHILADELPHIA, PENNSYLVANIA, ASSIGNOR TO PROCTOR & SCHWARTZ, INCORPORATED, OF PHILADELPHIA, PENNSYLVANIA, A CORPORATION OF PENNSYLVANIA.

MEANS FOR ATTACHING GARNETT TEETH TO CYLINDERS.

Application filed October 27, 1927. Serial No. 229,176.

The object of my invention is to provide means for securing garnett toothed strips to a cylinder by a separate strip having retaining means which overlaps the toothed strip.

5 A further object of the invention is to provide the retaining strip with a spring retainer, which will allow the tooth to be forced into position past the spring-retaining member, which in turn will hold the toothed strip 10 in position when seated in the groove of the cylinder.

In the accompanying drawing:

Fig. 1 is a sectional view of a cylinder of a Garnett machine, illustrating the improved 15 means for retaining the toothed strip on the cylinder;

Fig. 2 is a sectional view showing the toothed strip being forced into position;

Fig. 3 is a sectional perspective view of a 20 portion of a toothed strip;

Fig. 4 is a sectional perspective view of a portion of the retaining strip;

Figs. 5, 6, 7 and 8 are views illustrating 25 modifications of the invention.

Referring to Fig. 1, 1 is a cylinder having a spiral groove 2 of the ordinary form cut therein. The convolutions of the groove are spaced apart sufficiently to form a base 4 for the toothed strip 3, which is wound spirally 30 upon the cylinder. The toothed strip, in the present instance, has a base 5, and projecting from the base are garnett teeth 6 of any suitable form. The teeth are narrower than the base so as to form a shoulder 7 at one side. 35 This shoulder is preferably beveled as shown in the drawings.

Located in the spiral groove 2 is a retaining strip 8 having a base 9 and a spring-retaining member 10. This retaining member 40 is made as clearly shown in Figs. 1 and 4, and is so proportioned that it will yield when the toothed strip is forced into the space between the two convolutions of the retaining strip as clearly shown in Fig. 2, and when the toothed strip 45 has been seated on the cylinder then the spring member of the retaining strip will spring into normal position over the shoulder 7 of the toothed strip, as shown in Fig. 1, retaining said strip in position on the cylinder,

the convolutions of the retaining strip holding the toothed strip laterally in position. By this means the retaining strip can be wound upon the cylinder, and then the toothed strip as it is wound upon the cylinder will be forced past the spring member of the retaining strip, 55 as clearly shown in the drawings.

While Fig. 1 illustrates the retaining member as projecting upwards from the centre of the retaining strip, Fig. 5 illustrates the spring member 10^a projecting from one 60 edge of the strip 8^a, providing a long spring tongue.

Fig. 6 illustrates a retaining strip 8^b having a longitudinal slot 11 therein, forming a solid abutment 12 for a toothed strip and a 65 spring member 10^b.

In Fig. 7 the toothed strip 3^a has two shoulders, 7^a and 7^b, the shoulders 7^a being at one side of the toothed strip, and the shoulders 7^b being at the opposite side. In 70 this instance, the retaining member 8^c has a longitudinal slot 13 therein, separating two yielding sections or tongues 10^c and 10^d, one spring tongue engaging the shoulders 7^a and the other the shoulder 7^b. 75

In Fig. 8 is shown a retaining strip made in two parts, a base 9^d and a spring member 10^e, secured in a stop in the base.

Other forms of retaining members may be made without departing from the essential 80 features of the invention.

While the invention is particularly adapted for retaining garnett toothed strips on cylinders, it can be used for retaining other forms of toothed strips on cylinders. 85

I claim:—

1. The combination of a cylinder; a retaining strip thereon having a spring member; and a toothed strip shaped to be engaged by said spring member when in position. 90

2. The combination of a cylinder having a spiral groove therein; a retaining strip located in the groove and extending beyond the periphery of the cylinder to a spiral groove for a toothed strip; a toothed strip located in the last-mentioned groove, said toothed strip having a shoulder at one side; and a retaining member having a spring section ex- 95

tending over the shoulder when in its normal position and acting to retain the toothed strip on the cylinder.

3. The combination of a cylinder having a spiral groove therein; a retaining member located in the groove and having a bent spring section extending at one side beyond the edge of the base of said member; a toothed strip

located between the convolutions of the retaining member and having a shoulder at one side, the shoulder being beveled so as to allow the spring section of the retaining strip to seat itself on the shoulder when the toothed strip is seated. 10

THOMAS W. ALLEN.
